US0D1079672S

(12) **United States Design Patent** (10) Patent No.: **US D1,079,672 S**
(45) Date of Patent: ** Jun. 17, 2025

(54) **EARPHONE**

(71) Applicant: **Strand Industries, LLC**, Woodland Hills, CA (US)

(72) Inventor: **Ryan Parry**, Los Angeles, CA (US)

(73) Assignee: **Strand Industries, LLC**, Woodland Hills, CA (US)

(**) Term: **15 Years**

(21) Appl. No.: **29/908,899**

(22) Filed: **Jan. 16, 2024**

(51) LOC (15) Cl. **14-01**

(52) U.S. Cl.

USPC **D14/223**

(58) **Field of Classification Search**

USPC D14/223; D24/174; 128/864-866;

D13/108; 381/380-381, 322, 328

CPC H04R 1/10; H04R 25/00; H04R 25/02;

H04R 1/1066; H04R 1/1016; H04R

5/033; H04R 5/0335; H04R 1/08

Adam Diamant

(57) **CLAIM**

The ornamental design for an earphone as shown and described.

DESCRIPTION

FIG. 1 is a perspective view of an earphone of my new design;

FIG. 2 is a top view of the earphone shown in FIG. 1;

FIG. 3 is a bottom view of the earphone shown in FIG. 1;

FIG. 4 is a right side view of earphone shown in FIG. 1;

FIG. 5 is a left side view of earphone shown in FIG. 1;

FIG. 6 is a front view of the earphone shown in FIG. 1; and,

FIG. 7 is a rear view of the earphone shown in FIG. 1.

The broken lines depict portions of the earphone that form no part of the claimed design.

1 Claim, 7 Drawing Sheets
